UNITED STATES PATENT OFFICE.

SIMON MASSEL, OF NEW YORK, N. Y.

FUR-CUTTING MACHINE.

Application filed June 1, 1927. Serial No. 195,819.

My invention relates to machines for cutting furs and the same has for its object more particularly to provide a simple, efficient and reliable machine in which the 5 parts are so arranged and combined as to facilitate the operations required, in a manner to produce the best results possible with least danger of injury to or waste of the fur.

10 Further it is an object of the invention to provide a machine with a cutting mechanism by means of which the skin of the fur may be cut along predetermined lines without cutting or severing or otherwise injuring the hair which extends from the skin.

15 Further the invention has for its object to provide a machine in which provision is made to hold the skin stretched across the knife-gap in such a manner that the knife 20 may operate without injuring the fur fabric or hair.

Further it is an object to provide separate holding means for the fur at the front and back of the machine either of which may be 25 set first accordingly as the operator finds most convenient, the one first set holding the skin while the operator draws it taut across the knife gap and secures it by setting the other holding device.

30 Further it is an object to provide one of the holding devices with a contour that follows the contour of the knife-gap and to provide the other as a straight holding element extending across the machine, the 35 holding devices being in the nature of combs, the straight comb being preferably the one first to be set in order to enable a uniform stretching tension to be placed on the skin in stretching it across the knife-gap, thereby preventing wrinkles in the fur 40 which might interfere with the production of a clean cut.

Further it is an object to provide the straight holding comb with gaps that align 45 with the adjacent apexes of the knife and knife-gap in order to insure a more perfect cutting of the fur at the apexes of the zigzag edges.

50 Further it is an object of the invention to provide a simple, quick-releasable means for securing the fur holding combs down in the holding position independently one of another so that either may be secured or released at will.

Further the invention has for an object 55 to provide spaced guide plates with which the holding combs cooperate, the guide plates having opposing edges shaped to the contour of the knife blades and spaced apart a distance sufficient to constitute the knife-gap, one of the plates at least being adjustable toward and from the other to permit widening or narrowing of the knife-gap in order to accommodate furs having different 60 lengths of hair, without danger of cutting the hair or otherwise injuring it during the action of the knife.

Further it is an object to provide a zigzag cutting knife composed of a carrying 70 bar to which is separately secured a series of blades any of which may be removed for sharpening and replacement without disturbing the others, thereby making it unnecessary to remove the entire knife in order to sharpen it should one portion of the knife 75 become dull.

Other objects in part will be obvious and in part be pointed out hereinafter.

To the attainment of the aforesaid objects and ends, my invention consists in the novel 80 details of construction and in the combination, connection and arrangement of parts, hereinafter more fully described and then pointed out in the claims.

In the accompanying drawings, showing 85 an illustrative embodiment of the invention,

Figure 1 is a perspective view showing a machine embodying the invention, in which the knife is shown in the elevated or retracted position, the rear comb down in the clamping position and the front comb elevated.

Figure 2 is a detail perspective view showing 90 a portion of the cutter bar and attached blades (the extension at one end of the cutter bar which acts as a guide being shown).

Figure 3 is a detail cross section showing 95 the guides, a piece of fur in position thereon (fur side down) and the straight comb and the zigzag comb in engagement with the fur to hold the same in position over the knife zigzag ready to be acted on by the zigzag knife.

Figure 4 is a view similar to Figure 3 100 showing the knife after it has passed through the fur and cut the same in zigzag form (also showing how the hair of the fur

is pressed downwardly by the knife into the knife-gap without severing any of the hair of the fur).

Figure 5 is an inverted plan view of a portion of the front comb.

Figure 6 is a rear view showing a piece of fur separated along a zigzag line, by my invention, the upper portion showing the fringe of the fur extending below the zigzag edge of the skin while the lower portion shows merely the zigzag edge of the skin with no fur along the zigzag edge.

Figure 7 is a rear view of two pieces of fur represented in Figure 6 as the same appears when sewed together.

Figure 8 is a view showing the face portion of the fur (in this view the meeting edges of the skin where the same are sewn together are obliterated due to the zigzag cutting of the fur and the lapping of the hair over the cut).

In the drawings in which like numerals of reference indicate like parts in all the figures, 1 is the base which carries the uprights 2, the latter being cross-connected at their tops by plates 3; the base 1, uprights 2 and connecting plate 3 constitute the frame of the machine.

The uprights 2 have parallel vertically disposed guide slots 4 in which the ends of the comb holding bars 13 and 24 are mounted for vertical movement.

The uprights 2 each also have a vertical slot 5 in which the frame ends 7 of the zigzag knife bar 6 are located and have up and down movement.

The knife, whose construction is one of the features of my invention, comprises a bar 6 bent into a zigzag form, save at its ends, which ends are flat, lie in the same plane, and act as guides in cooperation with the slots 5. To this bar 6 is secured (preferably by screws 10) a series of blade sections 8 whose meeting edges are in complete contact so as to leave no substantial space between the same. The blades have V-shaped cutting edges 9 as shown.

Suitably located handles 11 are attached to the bar 6 in order that the bar may be conveniently pressed down to effect the cut, and, in order that the knife may be held up out of the way when not in use, it may be mounted on springs 12 suspended from the plate 3.

The rear holding device comprises a comb-bar 13 that carries the comb blade 14 whose teeth 15 serve to engage the skin and hold it down on the guide plate 34 hereinafter again referred to.

The comb 14 has its teeth 15 arranged in groups, each group being spaced apart to provide gaps 16, the centers of which are located in alignment with the adjacent apexes of the knife-gap 38. This arrangement insures more perfect cutting of the fur at the apexes of the zigzag edges.

On the upper side of the rear comb-bar 13 is provided sets of apertured ears 17 which constitute bearings for the latch rods 18, the latter being provided at their adjacent ends with finger pieces 19 and at their remote ends with detents 20 and detent springs 21. The detents 20 cooperate with racks 22 on the opposed faces of the uprights 2 to hold down the bar 13 in any position at which it is pressed.

In order to hold the comb-bar 13 elevated when it is not being used as well as to cooperate with the detents 20 and racks 22 in holding the bar placed, suitable springs 23 are suspended from the plates 3 and connected to certain of the ears, as clearly shown in Figure 1.

It will be noted that the teeth 15 of the rear comb are located in a straight line across the width of the machine, the purpose of which will later appear.

Another holding device is provided in the front of the machine to cooperate with the rear holding device just described. This front holding device comprises a comb-bar 24 to which is suitably secured the blades 25 which have teeth 26. It will be noted that the blades 25 and their teeth 26 lie in zigzag order following the contour of the zigzag knife-gap, the reason for which will later appear.

Apertured ears 27 on the top of the bar 24 constitute bearings for the latch rods 28, which like the rods 18, have finger pieces 29, detents 30 and detent springs 31. Racks 32 are also provided on the uprights 2 to cooperate with the detents 30 in the same manner as the racks 22 cooperate with the detents 20.

Suspending springs 33 are connected with the plates 3 and to ears 37 as shown.

Located on the base 1 directly beneath the combs 14 and 25 are the guide plates 34 and 36 respectively. At least one of these plates is adjustable toward and from the other to widen or restrict the knife-gap 38 as desired.

In the drawings I have shown the rear plate 34 secured by screws 35 in a non-adjustable manner while the front plate 36 is adjustably fastened at 37 to the base 1.

The fur skin is indicated in the drawings by the reference numeral 39 and the hair by the numeral 40 while the stitching by which the two pieces are sewn together is indicated in Figure 7 by the numeral 41.

Operation.

In operation, the guide plates 34 and 36 are first adjusted to the proper width, whereupon a piece of fur is laid over the guides as indicated by the dotted lines in Figure 1. Then the rear comb teeth 15 are brought into engagement with the skin side of the fur. As soon as the bar 13 which carries the comb 14 is lowered into engagement with the fur, the spring detents 20 at each end immedi-

ately engage with the corresponding racks 22 provided upon the inner sides of the vertical standards of the frame. The fur is then suitably stretched by hand over the guide plates and the front zigzag comb is lowered into position as illustrated in Figures 3 and 4. As soon as the front comb has been lowered the spring pressed detents 30 will engage with their respective racks 32 and hold the comb to its adjusted position and the fur firmly stretched between the combs. The knife bar 6 is then lowered by hand, the operator grasping the handles 19 and bringing the zigzag edge 9 of the blades into engagement with the fur and cutting the same as indicated in Figures 3 and 4.

Attention is called to the fact that by reason of the provision of the rear comb with teeth in straight alignment transversely 20 of the machine, the operator can the more readily stretch the fur smoothly across the knife-gap 38 and inasmuch as the rear comb has its groups of teeth spaced apart to provide the gaps 16 which align with the apexes 25 of the recesses, a more perfect cutting of the fur at the apexes is obtained when the cutting knife descends.

As soon as the cutting operation has been performed the knife will be raised by the 30 springs 12 and thereupon the comb bars 13 and 24 are released by pressing together the finger pieces at the center of the bars, whereby the detents at the ends thereof are released of their engagement with their respective racks and the springs 23 and 33 serve to raise the comb bars to their inoperative position.

It will be noted that the knife does not come in contact with the walls of the knife-gap as a shear but the gap is of larger area 40 than the cross sectional area of the blades. The reason for this is that in cutting the skins the blades will push aside the fur or hair as indicated in Figure 4 so that when 45 the skin is removed from the apparatus it will have a projecting fringe of hair as indicated at 40 in Figure 6. The corresponding part of the skin which has been severed will have a smooth edge as indicated in the lower 50 half of Figure 6.

It should also be understood that the cutter bar 6 should be so adjusted within the guideways 5 that when the same is in the lowermost position the edges of the cutting 55 blades cannot engage or touch the upper surfaces of the base so as to prevent all liability of injury to the hair of the fur (see Figure 4).

While my invention has been particularly 60 designed for use in cutting fur or animal pelts it is obvious that it is equally applicable to cutting fabric having a pile on one side.

Having thus described my said invention,

what I claim and desire to secure by Letters 65 Patent is:

1. In a fur cutting machine, the combination with spaced guide plates and a reciprocable knife whose blade operates in the space between said plates, of two independently operable means for holding the fur down on the guide plates and stretched over the space between said plates. 70

2. In a fur cutting machine, the combination with spaced guide plates and a reciprocable knife whose blade operates in the space between said plates, of two independently operable means for holding the fur down on the guide plates and stretched over the space between said plates, said holding 75 means each comprising a comb carrying bar, a comb carried by each bar, guideways for the bars, and means for yieldably suspending said bars one above each guide plate in cooperative association with the same. 80

3. In a fur cutting machine, the combination with spaced guide plates and a reciprocable knife whose blade operates in the space between said plates, of two independently operable means for holding the fur down on the guide plates and stretched over the space between said plates, said holding 90 means each comprising a comb carrying bar, a comb carried by each bar, guideways for the bars, and releasable means for holding the bars down to secure the fur. 95

4. In a fur cutting machine, the combination with spaced guide plates and a reciprocable knife whose blade operates in the space between said plates, of two independently operable means for holding the fur down on the guide plates and stretched over the space between said plates, said holding 100 means each comprising a comb carrying bar, a comb carried by each bar, guideways for the bars, and means for yieldably suspending said bars one above each guide plate in cooperative association with the same, and releasable means for holding the bars down 105 to secure the fur. 110

5. In a fur cutting machine, a frame including a base and uprights, the latter having cutter bar and comb-bar guideways, a vertically reciprocable cutter bar having its ends located in certain of said guideways, front and back comb bars mounted in the other guideways, said cutter and said comb-bars being independently movable, means yieldably suspending said bars above the base, guide plates having a knife gap between them located beneath the cutter and comb-bars and cooperating therewith, a cutting knife carried by the cutter bar, combs carried by the comb-bars, and means to secure the comb bars with their combs down 120 over the guide plates to hold a piece of fur stretched across the knife gap. 125

6. In a fur cutting machine having a suit-

able frame including a base and uprights with guideways, the combination with spaced guide plates mounted on the base, of a cutting knife mounted in certain of said guideways and adapted to be moved down and up into and out of the space between the guide plates, fur holding combs mounted in others of said guideways one above each guide plate, said knife and said space being of zigzag contour, one of said combs having a row of teeth in straight alignment across the width of the machine, the other comb having its teeth arranged in zigzag form conforming with the contour of said knife and said space for the purposes specified.

7. In a fur cutting machine having a suitable frame including a base and uprights with guideways, the combination with spaced guide plates mounted on the base, of a cutting knife mounted in certain of said guideways and adapted to be moved down and up into and out of the space between the guide plates, fur holding combs mounted in others of said guideways one above each guide plate, one of said combs having a row of teeth in straight alignment across the width of the machine.

8. In a fur cutting machine, a frame comprising a base, uprights and a cross plate connecting the uprights, guide plates mounted on said base between said uprights, one of said guide plates being adjustable toward

and from the other to provide a variable knife-gap, a knife mounted in said frame for reciprocation into and out of said knife-gap, the knife and knife-gap having the same contour, a straight-line comb mounted over and cooperating with one guide plate, a zigzag comb mounted over and cooperating with the other guide plate, the zigzag comb conforming in contour to that of the knife and knife-gap, the straight-line comb having its teeth arranged in groups with spaces between adjacent groups, the centers of which spaces align with the adjacent apices of the knife-gap.

9. In a fur cutting machine, the combination, with a pair of guide plates spaced apart to constitute a knife-gap and a knife mounted for reciprocation into and out of said gap, of a holding-down comb located above each guide plate, means to mount each comb for up and down movement independently one of the other, and means for holding said combs down on the fur with retaining pressure against the guide plates, substantially as specified.

Signed at the city of New York, borough of Manhattan, in the county and State of New York, this twenty-eighth day of May, 1900, one thousand nine hundred and twenty-seven.

SIMON MASEL.
